Primary Examiner — Sandra Snapp*Assistant Examiner* — Ieisha N Price(74) *Attorney, Agent, or Firm* — Nixon & Vanderhye P.C.(57) **CLAIM**

The ornamental design for a fastening device, as shown and described.

DESCRIPTION

FIG. 1 is a rear, top, right side view of a fastening device;
 FIG. 2 is a front, bottom, left side perspective view thereof;
 FIG. 3 is a bottom view thereof;
 FIG. 4 is a top view thereof;
 FIG. 5 is a rear view thereof;
 FIG. 6 is a front view thereof; and,
 FIG. 7 is a left side view thereof, the right side being a mirror image of.

1 Claim, 7 Drawing Sheets(56)
